Attorney

UNITED STATES PATENT OFFICE.

THOMAS WIDDOP, OF BURNTFORK, WYOMING.

GLAZIER'S TOOL.

SPECIFICATION forming part of Letters Patent No. 761,570, dated May 31, 1904.

Application filed June 3, 1903. Serial No. 159,946. (No model.)

To all whom it may concern:

Be it known that I, THOMAS WIDDOP, a citizen of the United States, residing at Burntfork, in the county of Sweetwater and State of Wyoming, have invented new and useful Improvements in Glaziers' Tools, of which the following is a specification.

My invention has relation to improvements in glaziers' tools; and it consists in the construction and arrangement of parts, as will be hereinafter described, and particularly pointed out in the claim.

In the accompanying drawings, Figure 1 is a perspective view showing the manner in which my tool is employed in placing a single glazier's point in position upon a side strip of a sash; and Fig. 2 is a side elevation of the tool, showing the manner of using the same in applying a point to an intermediate cleat 20 of the sash.

Referring to the figures of the drawings by numerals of reference, 1 are jaws, formed of any suitable metal, which are pivoted together and provided with shanks 2, one of 25 which has a squared upper end, as shown at 3, and a spring 4 is preferably interposed between the two shanks, so as to hold the jaws 1 normally separated. The terminal ends of the jaws are angularly cut away within 30 said ends to form a rectangular recess 5, said recess being constructed to conform to the configuration of the putty-strips of the window-sash, so as to clamp a sash-point to the upper edge and sides of the putty-strip to hold 35 the panes of window-glass in position.

This tool is adapted to be used in connection with glaziers' points such as described in my application for patent of even date herewith, and said points are preferably formed 40 of retaining-plates 6, having angular extensions 7 and inwardly-extending prongs 8. Two forms of points are employed, one for use upon the side rails of a window-sash, as shown in Fig. 1, and the other for use upon 45 the intermediate putty-strips of the window-sash, as shown in Fig. 2. Where the point is to be used in connection with a side strip, the plate 6 is placed on the glass, and the prong extending from said plate is forced into 50 the strip by driving the squared end 3 of

shank 2 thereagainst. Said shank is then held in position against the point, while a hammer 9 or other suitable tool is employed for driving the other prong 8 into the outer faces of the strip. Where it is desired to 55 fasten a point to an intermediate putty-strip of the sash, said point is placed within the recesses 5 in the jaws 1, and the distance between the points of the inwardly-extending prongs 8 is normally greater than the thickness 60 of the cleat. Said point is then placed over the putty-strip until the plates 6 are brought into contact with the glass, and shanks 2 are drawn together and will, as is obvious, press the point upon the putty-strip 65 and force the prongs into the opposite sides thereof, as shown in dotted lines in Fig. 2. It will be seen that the device is extremely simple and inexpensive in construction and is of great convenience in fastening points such 70 as herein described to window-sashes.

In the foregoing description I have shown the preferred form of my invention; but I do not limit myself thereto, as I am aware that modifications may be made therein without 75 departing from the spirit or sacrificing any of the advantages thereof, and I therefore reserve the right to make such changes as fairly fall within the scope of my invention.

Having thus described the invention, what 80 is claimed as new is—

A glazier's tool comprising spring-actuated jaws pivoted together, one of which is provided with a squared upper end, the jaws also having angular cut-away portions at their 85 lower ends on their inner opposing faces to form a rectangular recess within said ends, said recess being constructed to conform to the configuration of the putty-strip of a window-sash to secure a sash-point to the upper 90 edge and sides of said putty-strip which serves to hold the pane of glass between the putty-strips of a window-sash, substantially as specified.

In testimony whereof I affix my signature in 95 presence of two witnesses.

THOMAS WIDDOP.
